UNITED STATES PATENT OFFICE

2,331,481

INSULATOR

Herman S. Krueger, Niagara Falls, N. Y.

Application October 13, 1942, Serial No. 461,889

2 Claims. (Cl. 191—32)

This invention relates to improvements in insulators, and it has particular relationship to insulators which are now in use on mono rail hoists, and the objects of my improvement are as follows:

First, to provide an insulator particularly well adapted for use where it is exposed to moisture due to climatic and building conditions.

Second, to provide an insulating structure through which a bolt or rod iron extends to support the insulating structure from below or from above and which includes conductor clamping means of non-conducting material.

Third, to provide an insulator consisting of three or more parts, two of which are of equal design so that they can be interchanged.

Fourth, to provide a simple device for the purpose stated above, which is light in weight and simple in construction to be manufactured and sold at a very reasonable price.

Further objects of the instant invention reside in any novel feature of construction or operation or novel combination of parts present in the embodiment of the invention described and shown in the accompanying drawing.

In the drawing:

Fig. 1 is a front elevation of the insulator; Fig. 2, a side elevation of the insulator; Fig. 3, a bottom plan view of the insulator; Fig. 4, a front elevation of a modification of a part of the insulator; and Fig. 5, a plan view of this modification.

Similar numerals refer to similar parts throughout the several views.

In Figs. 1 to 3 the numeral 1 designates a T-shaped top plate of porcelain or other suitable dielectric material having an aperture 2 in its center and grooves 3 for a break in moisture on its face 4, on the bottom 5 of its broader part, on its front side 6, and on its rear side 7. A bottom plate 8 is of exactly the same design and material and is also provided with the same grooves 3 as the top plate 1; so that if a top or bottom plate breaks, it can be replaced by a duplicate of either a top or a bottom plate.

Between the top plate 1 and the bottom plate 8 are U-shaped plates 9 and 10 of porcelain or other suitable dielectric material. Each of these plates 9 and 10 has an aperture 11 in its center and two ledges 12 adjacent the inner side of each flange 14. The ledges 12 are adapted to support the contact rails 15. The plates 9 and 10 are also provided with grooves 3 adjacent the ledges 12 as well as at the front and rear sides. One of the U-shaped plates is provided with spacing

5 posts 16 to keep the plate 9 spaced at a distance from the plate 10 so that air can pass through between the plates 9 and 10. In the present instance, plate 10 is provided with four spacing posts 16.

According to the modification of the invention shown in Figs. 4 and 5, one double-T-shaped plate 17 can be used instead of the two U-shaped plates 9 and 10. The top and bottom sides 18 and 19 of plate 17 are of the same design as the top side 20 of plate 9, and the plate 17 is also provided with an aperture 11, with ledges 12, and with grooves 3.

The apertures 2 and 11 can be made as round holes large enough to allow a threaded hanger bolt 21 to pass through. However, I prefer to provide the apertures with drain slots 22 to drain any water which might form on or in the insulator.

20 In order to prevent the plates from being pressed toward each other too strongly when tightening the nut 23, what might result in a cracking of the plates, a spring or an elastic washer 24 is placed between the nut 23 and the plate 1. This elastic washer may be of any approved design, preferably consisting of a piece of sheet steel, the ends 25 of which are bent inwardly as shown in Fig. 1. The washer 24 is provided with an aperture in its center for the 25 passing through of the bolt 21.

While there has been shown and described and pointed out the fundamental novel features of the invention as applied to only two modifications, it will be understood that various omissions 35 and substitutions and changes in the form and details of the device illustrated may be made by those skilled in the art without departing from the spirit of the invention. It is the intention, therefore, to be limited only as indicated by the 40 scope of the following claims.

What is claimed is:

1. An insulator comprising a T-shaped top plate of insulating material having an aperture in its center and grooves for a break in moisture 45 on the face, on the bottom, on the front side and on the rear side of its broader part; a bottom plate of insulating material being of exactly the same design as said top plate; two U-shaped intermediate plates of insulating material between said top and bottom plates, each of said U-shaped plates having two ledges adjacent the inner side of each flange to support contact rails clamped between said top, bottom and intermediate plates, grooves for a break in moisture adjacent said ledges and at the front and rear

sides, and an aperture in its center placed at a distance from said ledges; spacing posts between said U-shaped plates; a threaded bolt extending through said apertures and adapted to support the insulator; a nut on said bolt; and an elastic washer between said nut and the insulator, substantially as described.

2. An insulator comprising T-shaped top and bottom plates of insulating material, each having an aperture in its center and grooves for a break in moisture on the face, on the bottom, on the front side and on the rear side of its broader part; a double-T-shaped insulating plate between

said top and bottom plates, said double-T-shaped plate having four ledges adjacent the inner side of each flange to support contact rails clamped between said top, bottom and intermediate plates, grooves for a break in moisture adjacent said ledges and at the front and rear sides, and an aperture in its center placed at a distance from said ledges; a threaded bolt extending through said apertures and adapted to support the insulator; a nut on said bolt; and an elastic washer between said nut and the insulator, substantially as described.

HERMAN KRUEGER.
